UNITED STATES PATENT OFFICE.

CLEMENT A. HARDY, OF MOLINE, ILLINOIS, ASSIGNOR TO THE FULLER MANUFACTURING COMPANY, OF EAST MOLINE, ILLINOIS.

GRAIN-DRILL.

SPECIFICATION forming part of Letters Patent No. 732,633, dated June 30, 1903.

Application filed January 19, 1903. Serial No. 139,661. (No model.)

To all whom it may concern:

Be it known that I, CLEMENT A. HARDY, a citizen of the United States, residing at Moline, in the county of Rock Island and State 5 of Illinois, have invented a new and useful Grain-Drill, of which the following is a specification.

This invention relates to grain-drills, and more especially to that class of drills which are known as "shoe-drills," in which a shoe or runner is employed for the purpose of opening the furrow. Practical experience has long taught the desirability of using pressure, such as spring-pressure, for the 15 purpose of holding the shoe or runner to its work in order that the furrows may be opened evenly and at an equal depth instead of relying simply upon the weight of the runner comprising the shoe, the seed-tube, and related parts. In using such spring-pressure, however, several points are to be considered. Thus it is of importance that the pressure be evenly applied and in such manner as to prevent vibration, which would seriously interfere with the accuracy of the work. Again, it is desirable that the pressure of each spring be capable of regulation and adjustment. Again, it is desirable that the pressure be applied at a point as close as possible to the 25 discharge end of the seed-tube, where it will be most effective. It is also desirable that the spring attachment should be of such a nature that it will always operate with freedom and certainty and without liability of becoming 30 clogged or otherwise interfered with during the progress of the operation of the machine of which it forms a part.

My invention therefore aims to produce a spring attachment for grain-drills which shall 35 possess these and other advantages.

With these ends in view the invention consists in the improved construction, arrangement, and combination of parts, which will be hereinafter fully described, and particularly pointed out in the claims.

In the accompanying drawings, Figure 1 is a perspective view showing the runner of a grain-drill having my improvement applied thereto. Fig. 2 is a vertical sectional view 45 taken through the lower end of the seed-tube

and the socket in which is mounted the lower end of the flat spring. Fig. 3 is a sectional detail view taken transversely through the springs and clamping members.

Corresponding parts in the several views 55 are indicated by similar characters of reference.

1 designates the shoe or furrow-opener, 2 2 the drag-bars, and 3 the seed-tube, all of which are of the ordinary construction with 60 the exception that the seed-tube has formed upon its front side a bracket 4, which is recessed to form a socket 5 for the reception of the lower end of a flat spring 6, which may be secured by means of a bolt 7. The bracket 65 having the socket 5 is upon the front side of the seed-tube and is inclined in an upward and forward direction, so that the spring 6 will extend upwardly and forwardly, as shown, the upper end of said spring being 70 bent so as to lie approximately in a horizontal plane, its forward end terminating at a point between the drag-bars 2. The forward end of the spring 6 is formed with an eye 8, through which passes the bolt 9, upon the 75 ends of which are mounted a pair of round spring-rods 10, having eyes 11 at their front ends to engage the bolt 9 and also provided at their rear ends with eyes 12 to engage a connecting-bolt 13, the said spring-rods 10 10 80 being disposed on opposite sides of the seed-tube, which latter is free to move vertically between the said spring-rods.

The flat spring 6 and the spring-rods 10 10 at the sides thereof are connected by means 85 of a clamping device consisting of upper and lower clamping members 14 14, the opposing faces of which are provided with recesses 15 to accommodate the rods 10, said clamping members being connected by means of bolts 90 16, disposed between the spring 6 and rods 10, as clearly seen in Fig. 3 of the drawings, and provided with nuts 17, which may be tightened so as to clamp the parts securely together. It will thus be seen that the spring 95 6 and the spring-rods 10 are connected to form virtually a single spring member which by exercising a downward pressure upon the rear ends of the rods 10 will operate to exert a downward pressure upon the seed-tube at 100

the point where the latter is connected with the spring 6, which point, as will be seen, is directly above the shoe or furrow-opener.

The connecting-bolt 13 at the rear ends of 5 the spring-rods 10 is connected by a yoke 18 with an operating-link 19, which may be actuated by lever-power or in any convenient manner to set the spring and to regulate the pressure thereof. It is obvious that in a machine equipped with a number of runners, as 10 is usually the case, the operating-links of the several springs may be so connected as to enable the several springs to be simultaneously set or regulated.

15 While the spring-pressure may be adjusted by means of the operating-link 19 so as to cause the runner to engage the ground with any desired degree of pressure, according to the condition of the soil, it will be seen that 20 the tension of the individual springs is capable of being minutely regulated by means of the clamping device comprising the members 14, which may be adjusted at any desired distance from the connecting-point of the spring 25 members 6 and 10 to increase or diminish the tension. By the construction and arrangement of parts herein shown and described such adjustment may not only be quickly and easily but very accurately effected, this being the feature which I consider of great advantage.

30 My improved spring attachment, as will be seen from the foregoing description, is extremely simple as to the construction thereof 35 and of such a nature as to operate efficiently to effect the desired result. The spring-pressure, as will be seen, is applied directly to the seed-tube and is capable of being minutely regulated. By the construction de- 40 scribed I attain absolute certainty of action and without the least tendency to vibration, while at the same time perfect flexibility of movement is secured, the importance of which will be readily appreciated.

45 My improved spring attachment is strong and durable and not liable to get out of order, there being no place where dirt may lodge in such a manner as to interfere with the effective operation of the spring.

50 I have in the foregoing described a simple and preferred form of my invention; but I desire it to be understood that I do not limit myself as regards structural details, but reserve the right to all changes, alterations, and 55 modifications which may be resorted to without departing from the spirit of my invention or sacrificing the utility of the same.

Having thus described my invention, I claim—

1. In a device of the class described, the 60 combination with the runner and seed-tube, of a spring rigidly attached to the seed-tube at a point closely above the rear end of the shoe and extending in a forward direction, auxiliary spring-rods connected with the front 15 end of said spring and extending rearwardly, hugging the sides of the seed-tube and adjustable clamping means connecting said spring and auxiliary spring-rods.

2. In a device of the class described, the 70 combination with the runner and seed-tube, of a spring rigidly attached to the seed-tube at a point closely above the rear end of the shoe and extending in a forward direction, auxiliary spring-rods connected with the front 75 end of said spring and extending rearwardly hugging the sides of the seed-tube, adjustable clamping means connecting the said spring and auxiliary spring-rods, and a yoke connecting the rear ends of the latter with an operating-link.

3. In a device of the class described, the seed-tube having a forwardly-extending socketed bracket, a spring mounted therein and extending upwardly and forwardly, said 85 spring being bent to dispose its forward end in an approximately horizontal plane, rods connected with the front end of said spring and disposed on either side thereof, said rods being extended rearwardly on either side of 90 the seed-tube and there connected, and clamping means adjustably connecting said spring and rods.

4. In a device of the class described, the seed-tube having a forwardly-extending socketed bracket, a spring mounted therein and extending upwardly and forwardly, rods connected with the front end of said spring and disposed on either side thereof, said rods being extended rearwardly on either side of the 100 seed-tube and there connected with an operating-link, and an adjustable clamp connecting said spring and rods, said clamp comprising upper and lower clamping members recessed in their opposing faces to accommodate 105 the rods and connected by bolts disposed between said rods and the intermediate spring.

In testimony that I claim the foregoing as my own I have hereto affixed my signature in the presence of two witnesses.

CLEMENT A. HARDY.
